W. E. PORTER

CASE FOR STEM WINDING AND STEM SETTING AUTOMOBILE CLOCKS

Filed Sept. 12, 1922

Inv. Ctor
Wilson E. Porter
in Seymour & Earley
Atty

UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

CASE FOR STEM-WINDING AND STEM-SETTING AUTOMOBILE CLOCKS.

Application filed September 12, 1922. Serial No. 587,662.

To all whom it may concern:

Be it known that I, WILSON E. PORTER, a citizen of the United States, residing at New Haven, in the county of New Haven and State of Connecticut, have invented a new and useful Improvement in Cases for Stem-Winding and Stem-Setting Automobile Clocks; and I do hereby declare the following, when taken in connection with the accompanying drawings and the characters of reference marked thereon, to be a full, clear, and exact description of the same, and which said drawings constitute part of this application, and represent, in—

Fig. 1, a view in front elevation of a stem-winding and stem-setting automobile clock, cased in accordance with my invention and shown as mounted in an instrument-plate, portions of which are broken away.

Fig. 2, a view thereof in side elevation, with the instrument-plate in vertical section.

Fig. 3, a view in transverse section on the line 3—3 of Fig. 1.

Fig. 4, a plan view of the clock-case as inserted into the instrument-plate from the rear thereof, with its clamping-ring, mounting-yoke and retaining-nuts in position for assemblance therewith.

Fig. 5, a detached plan view of the removable bezel of the case.

Fig. 6, a broken, detail, sectional view of the clamping-ring, removable bezel, dial-mat and glass.

My invention relates to an improvement in cases for that class of stem-winding and stem-setting clocks designed to be installed in the instrument-plates of automobiles, the object being to produce a simple, strong, and efficient clock-case constructed with particular reference to facilitating the initial installation of eight-day clocks of the character described, with provision for their easy regulation from the front of the clock at any time without demounting the same.

With these ends in view, my invention consists in an automobile clock-case having certain details of construction and combinations of parts as will be hereinafter described and particularly pointed out in the claims.

In carrying out my invention, as herein shown, I employ an annular, removable clamping-ring 10 having a milled edge and

formed upon its inner face with an externally-threaded sleeve 11 adapting it to be screwed into internal threads 12 formed just within the open outer end of a deep cylindrical case 13 receiving a clock-movement 14 which may be of any approved construction, and is, preferably, an eight day movement. The said ring 10 and its sleeve 11 are also internally threaded for the removable reception of a bezel 16 having an externally- and internally-threaded sleeve 15, the external threads of which engage with the internal threads of the clamping-ring and the internal threads of which receive the external threads of a removable dial-mat 17 which holds the glass or crystal 18 in place in the bezel 16. Under this construction, the bezel may be removed for regulating the clock without disturbing the clamping-ring, and so without demounting the clock, which is necessary when the bezel 16 is made to serve as the clamping-ring of stem-winding and stem-setting clocks inserted through the instrument-plate from the rear thereof.

The instrument-plate 19 is formed with a circular opening 20 just large enough to receive the clock-case 13, which is inserted into it from rear to front and firmly held in place by the engagement of the clamping-ring 10, with the forward face of the said plate 19 at points around the opening 20 and by the engagement with the rear face of the said plate at points adjacent to the said hole of the forward ends of the legs of a stiff rectangular yoke 21 adapted to embrace the case 13 and formed with holes 22 to permit it to be slipped over mounting-screws 23 projecting from the closed back of the case 13, in which they are rigidly mounted. The projecting outer ends of the screws 23 receive nuts 24, by which the yoke is drawn forward and the clock correspondingly drawn rearward in the plate 19, which will thus be clamped between the ring 10 and the forward ends of the legs of the yoke, whereby the clock is firmly installed in the plate.

The clock-movement 14, secured by pillars 25 in the case 13, is wound and set in the usual manner by a knurled finger-button 26, upon the lower end of a winding- and setting-stem 27 housed within a tube 28, the upper end of which is rigidly mounted in

the bottom of the case 13, which is of sufficient depth from front to rear for the reception of an eight-day clock-movement.

In the use of my improved clock-case, the 5 ring 10, together with the bezel 16, is removed from it, after which the open forward end of the case is readily passed from rear to front, through the opening 20 in the plate 19. The yoke 21 is now slipped over 10 the screws 23 and the binding-nuts 24 applied to the screws. The ring 10 having been screwed home in the projecting forward end of the case, the binding-nuts are screwed upon the screws 23 until the plate 19 is 15 pinched between the ring 10 and the ends of the legs of the yoke, whereby the clock is firmly installed in place. Now, if it is necessary to regulate the clock, this can be done very readily without demounting it, by simply removing the removable bezel 10.

I claim:

1. In a stem-winding and stem-setting automobile clock, the combination with a case provided at its forward end with internal screw-threads, of a removable clamping-ring provided with external screw-threads for engagement with the said internal screw-threads of the case, and also with internal screw-threads, and a removable 25 bezel having external screw-threads for engagement with the said internal screw-threads of the clamping-ring, whereby the bezel may be removed for regulating the clock from the front thereof without demounting the clock from the automobile.

2. In a stem-winding and stem-setting automobile clock, the combination with a case provided at its forward end with internal screw-threads, of a removable clamping-ring 30 provided with external screw-threads for engagement with the said internal screw-threads of the case, and also pro-

vided with internal screw-threads, a removable bezel having external screw-threads for engagement with the said internal screw-threads of the clamping-ring, and also having internal screw-threads, and a dial-mat having external screw-threads for engagement with the said internal screw-threads of the removable bezel, whereby the bezel may be removed for regulating the clock from the front thereof, without demounting the clock from the automobile. 45

3. In a stem-winding and stem-setting automobile clock, the combination with a case 50 provided at its forward end with internal screw-threads, of a removable clamping-ring having external screw-threads for engagement with the said internal screw-threads of the case and also having internal screw-threads, a removable bezel having external screw-threads for engagement with the said internal screw-threads of the clamping-ring, a plurality of screws projecting 55 from the back of the said clock-case, and a mounting-member fastened to the said clock-case by the said screws and extending forward with respect thereto into position to co-act with the said clamping-ring in mounting the clock in the instrument-board of an automobile, whereby the clock may be permanently installed in the said instrument-board and regulated from its front by the removal of the said bezel from the said ring without demounting the clock from the 60 70 said instrument-board.

In testimony whereof, I have signed this specification in the presence of two subscribing witnesses.

WILSON E. PORTER.

Witnesses:

MALCOLM P. NICHOLS,
GEORGE D. SEYMOUR.
